(57) **CLAIM**

The ornamental design for a horseshoe nail, as shown and described.

DESCRIPTION

FIG. 1 is a perspective view taken from point of the nail toward the rectangularly configured head of the nail;

FIG. 2 is a front side elevation view thereof showing the arcuate convex crown element at the head of the nail;

FIG. 3 is a right side elevation view thereof;

FIG. 4 is a rear elevation view thereof;

FIG. 5 is a left side elevation view thereof;

FIG. 6 is a top plan view thereof showing a substantially flat smooth surface at the end of the convex crown element at the head of the nail; and,

FIG. 7 is a bottom view thereof showing the point of the nail.
